Primary Examiner — Mark Goodwin(74) *Attorney, Agent, or Firm* — Cesari and McKenna, LLP; Michael R. Reinemann(57) **CLAIM**

I claim the ornamental design of a nozzle trigger chock, as shown and described.

DESCRIPTION

FIG. 1 is a front view of a nozzle trigger chock showing the new design;

FIG. 2 is a rear view thereof;

FIG. 3 is a top view thereof;

FIG. 4 is a bottom view thereof;

FIG. 5 is a left side view thereof, the right side being a mirror image thereof;

FIG. 6 is a perspective view thereof; and,

FIG. 7 is a sectional view taken along line 7-7 of FIG. 2.

The broken line showing of various surface features is included for the purpose of illustrating portions of the nozzle trigger chock and forms no part of the claimed design.
